(57) **CLAIM**

The ornamental design for the theft deterrent device, as shown and described.

DESCRIPTION

FIG. 1 is a perspective view of the theft deterrent device of the present invention.

FIG. 2 is a top plan view of FIG. 1.

FIG. 3 is a bottom plan view of FIG. 1.

FIG. 4 is a front elevation view of FIG. 1.

FIG. 5 is a rear elevation view of FIG. 1.

FIG. 6 is a right side elevation view of FIG. 1; and,

FIG. 7 is a left side elevation view of FIG. 1.
